UNITED STATES PATENT OFFICE.

PERRY A. BRICK, OF GALION, OHIO, ASSIGNOR TO THE NATIONAL GRAVE VAULT CO., OF GALION, OHIO, A CORPORATION OF OHIO.

SELF-DUMPING TRUCK.

Application filed March 4, 1926. Serial No. 92,369.

This invention relates to dumping trucks of that character where the body is mounted for rocking movement upon the frame or chassis of the truck, the body being so mounted upon the chassis that when it is in a horizontal position and released the body will tilt by gravity to an inclined position to discharge its load and after the load is discharged the body will return to its horizontal position by its own weight.

The invention particularly relates to improvements in the construction disclosed in the pending application of Ernest Eisenhut, filed February 3, 1925, Serial No. 6,608.

In this pending application there is disclosed a body tiltably mounted upon the truck frame or chassis as above stated, and a prop formed in two sections pivoted to each other and to the body and chassis respectively and so constructed that when a certain locking device is released and the body tilts to discharge the load the two sections of the prop will be brought into alignment and locked and when this lock is released and an initial impulse given to the body, the two sections of the prop will break and the prop will fold and permit the downward movement of the body.

One of the objects of the present invention is to provide in a construction of this character means for retaining the body in its horizontal or lowered position against any tendency to tilt; which means has a camming action against a part of the body and which means is so formed that as the truck body is tilted due to the truck moving over the road, the retaining means or latch will move farther and farther into operative engagement with the body and hold it tighter and tighter to the truck frame or chassis.

Still another object is to improve upon the details of construction of the prop and its latching means as illustrated in the aforesaid application of Eisenhut, such improvements rendering the operation of the prop more certain and positive and tending to simplify the construction.

Other objects will appear in the course of the following description.

My invention is illustrated in the accompanying drawings, wherein:—

Figure 1 is a fragmentary side elevation of a dumping truck constructed in accordance with my invention;

Figure 2 is a like view to Figure 1 but showing the body tilted;

Figure 3 is a top plan view of a portion of the upper section of the prop and spring;

Figure 4 is a fragmentary vertical section from front to rear showing in elevation the actuating and locking mechanism;

Figure 5 is a section on the line 5—5 of Figure 4;

Figure 6 is a like view to Figure 4 but showing the position of the parts when the body is in dumping position.

Referring to these drawings it will be seen that I have illustrated a portion of a dumping truck in which the frame or chassis of the truck includes longitudinal beams 10, which may constitute the top of the chassis frame. Mounted upon the beams at their rear ends is an approximately U-shaped angle iron 11 and at the rear ends of the arms of this angle iron there are disposed parallel short irons 12 and a plurality of transverse pins 13. The dumping body 14 is provided with a pair of sector shaped members 15 having teeth which mesh in the space between the pins 13 and the sector shaped members 15 and the pins 13 constitute a fulcrum upon which the dumping body tilts, this fulcrum being shiftable so that when the body 14 is in a horizontal position and loaded, the fulcrum will be forward of the middle of the body and hence the weight of the load will tend to tilt the body to a dumping position and when the body has been tilted to a dumping position the fulcrum will be rearward of the middle of the body so that when the load has been discharged the body will tend to return to its horizontal position.

The forward end of the body 14 is provided with a depending counterweight 16. This counterweight is illustrated as formed of two angle irons 17 and 18 attached to a downward extension of the front end plate of the body and connected by a plate 19 but I do not wish to be limited to this specific manner

of constructing the counterweight, however. This counterweight carries upon it the vertical angle irons 20, which support the latch pin 21. Mounted upon a transverse angle iron 22 are the vertical angle irons 23 and mounted upon a transverse pin 24 and carried by these angle irons 23 is the latch 25, this latch having an arcuate underface 26 which is eccentric to the pivotal axis of the latch in that the radius of the rear end of this latch is longer than the radius of the front end of the latch. The face 26 of this latch is adapted to engage over the latch pin 21 previously described, when the body is in a horizontal position.

Mounted in ears projecting upward from the angle iron 22 or in any other suitable manner is a shaft 27 which carries upon it the upwardly projecting trigger 28 which at its upper end has an upwardly projecting ear pivotally connected to the latch 25 by a link 29. This trigger 28 carries the transversely extending head 30 and below the shaft 27 is provided with the downwardly extending lug 31. This shaft 27 carries upon it the arm 32 which is connected by a rod or link 33 to a lever 34 mounted in any suitable manner upon the frame of the truck so that when this lever is pulled in one direction it will pull on the arm 32 and thus retract the latch 25 from its engagement with the latch pin. A spring 35 coiled around the shaft 27 acts to urge the shaft in a counter clockwise direction to thereby urge the latch into engagement with the latch pin and cause the turning of the arm 32.

Also mounted upon the shaft 27 is one section 36 of the prop, this section being formed of two parallel bars 37, as shown in Figure 5, disposed, one on each side of the hub of the trigger. This section 36 is pivoted at its outer end as at 38, to a prop section 39, having at its extremity a head 40, notched or grooved at its opposite ends to receive the U-shaped yoke 41. A compression spring 42 is disposed between the bight of the yoke and the head 40 and thus urges the yoke downward on the section 39. This yoke is pivoted upon a transversely extending pivot pin 43 in turn carried by depending ears 44, attached to the dumping body 14 in any suitable manner. Preferably these ears are provided with two apertures 45 for the passage of the pin 43 so that this pin may be adjusted in either of these passages.

The section 39 adjacent the pivot 38 is formed with a rounded corner 46 and with a recess 47 just above this rounded corner. Pivoted between the two members 37 of the section 36, is the prop latch 48 which is somewhat hook-shaped to provide a bill 49 engageable in the locking recess 47. This latch is urged in one direction by a spring 50 mounted upon a transversely

extending pin 51 or by any other suitable spring mechanism and the latch is provided with a hook or eye 52 on the under face of the latch. A connection 53 engages with this eye and extends rearward and engages with the arm 31 of the trigger 28. This connection must be either a flexible connection with a certain amount of slack or, as illustrated in Figure 4, this connection may consist of a rod 53 which has sliding engagement through an eye 55 formed in the arm 31. While this is the preferable construction I do not wish to be limited to it.

With the parts in the position shown in Figure 1, and the body of the truck locked, if it be desired to dump the load then a pull on the hand lever 34 produces a partial clockwise rotation of shaft 27 and trigger 28 which will pull the latch 25 rearward and out of engagement with the latch pin 21, the weight of the load will tilt the box lifting the front end thereof and causing the prop or "stiff arm" to straighten out until the points 27, 38 and 43 are approximately in line. The tilting motion is then stopped, the prop having reached its greatest possible extension and at this moment the spring 42 absorbs the shock. When the prop has reached the position where both sections are in alignment with each other the notch 47 will have arrived opposite the extremity 49 of the latch 48 which will be forced into the notch by the spring, thus holding the prop rigid and preventing its folding up. As soon as the front end of the box has started to rise after the initial actuation of the hand lever 34, the spring 35 will produce a counter clockwise rotation of the shaft 27 which will push the latch 25 forward and elevate the arm 31 to a point approximately level with the shaft 27. When the prop straightens out and the latch 48 engages in the notch 47 the connection 53, if this connection is merely a flexible chain or wire, should be loose enough not to hinder this movement. This is accomplished in the construction illustrated in Figure 4 by causing a sliding engagement between the rod 53 and the eye 55.

To bring the box back into its horizontal position a pull is exerted upon the hand lever 34 precisely like the pull exerted for the purpose of causing the box to tilt, this pull producing a clockwise rotation of the shaft 27 and trigger 28 and exerting a pull upon the connection 53, pulling latch 48 out of engagement with the notch 47. The connection 53 should be of such length that as soon as the latch 48 is out of engagement with the notch 47 the crosshead 30 on the trigger, will come into engagement against the upper or front side of the two bars 37 which constitute the lower section 36 of the prop. A small movement of the hand lever 34 is sufficient to produce this result and a further

movement of the hand lever 34 causes a continued clockwise rotation of the trigger 28 forcing the prop section 36 rearward and downward thus furnishing the initial impulse for folding up the prop and bringing the front end of the box downward. As soon as this initial impulse has been given the counterweight 16 acts to bring the box back to a horizontal position. Immediately after the initial impulse is given the hand lever 34 is released. The spring 35, of course, produces a counter clockwise rotation of the shaft 27, causing the latch 25 to move forward. As the forward end of the body with the counterweight moves downward the latch pin 21 will strike the inclined front edge of the latch 25 forcing the latch back until the latch pin 21 is below the front lower corner of the latch 25 whereupon the spring 35 will again force the latch 25 forward over the latch pin. The eccentric surface 26 of the latch causes a wedging action which continues until the counterweight 16 is down firmly on its seat and the latch 25 crowding in above the latch pin 21 so that there is no possibility of movement up or down of the front end of the box. It will be seen that resistance to upward movement of the latch pin 21 is not dependent upon the strength of spring 35 but that the relative position of the pin 21 and the pivot pin 24 is such that any upward movement of the latch pin 21 is in a direction toward the pin 24 and thus any upward movement is amply resisted and there is no possibility of the latch pin crowding the latch rearward. Thus even though the spring 35 becomes weakened so as to be unable to force the latch 25 against the pin 21 sufficiently to cause the crowding downward of the counterweight, an equivalent action can take place. The spring 35 must, of course, have sufficient strength to start the latch in over the pin 21 and preferably it will have sufficient strength to keep on shifting this latch forward so long as there is no resistance. As the truck starts to move and as it moves there will naturally be a tendency of the box to rock or jog upon its bearings and the upward thrust thus developed by the front end of the box will be checked by the latch 25 and any downward movement of the front end of the box or of the counterweight will permit the latch 25 to move forward and take up the lost motion or, in other words, any downward movement of the forward end of the box will permit the latch to crowd inward and exert a camming action upon the pin 21. Thus, I have provided a completely automatic device for latching the front end of the box and keeping it always free from any vertical play.

While I have illustrated the spring 35 for the purpose of oscillating the shaft 27 in one direction a weight might be used upon

the rear face of the latch, which weight would be sufficient to cause the latch to be urged forward towards a position where its upper face would be approximately horizontal.

It will be seen that this mechanism provides means for positively latching the truck body in its horizontal position and lowering the body from its tilted position, both of said means being released by a relatively slight movement of the hand lever but rendering it unnecessary for the operator to assist gravity in any way in tilting the body or returning the body to its horizontal position. This operation of the lever to permit a dumping movement of the body or the return of the body is secured without moving the chassis and without requiring the driver to dismount even from a closed cab, open any doors or windows of the cab, or even turn around. The gravity operated body can be held at a dumping angle just as long as required. The latch for holding the body in its horizontal position is so constructed as to take up any oscillation of the body and hold the body firmly down upon the chassis. After the initial impulse has been given either to dump the body or to return the body to its horizontal position the remainder of the operation is entirely automatic. By the provision of a plurality of bearing openings in the ears 44 I provide means whereby the extreme angle to which the body tilts may be adjusted.

It will be seen that I provide automatic means for latching the front end of the body and keeping it always tight down against the chassis and free from vertical play, and that this automatic crowding in of the latch can be secured either by a spring engaging the pivot upon which the latch is mounted, or otherwise engaging the latch, or by a weight urging the latch forward, and that this crowding action is secured by the eccentric curvature given to the under face of the latch which causes it to wedge into engagement with the pin or keeper 21.

I claim:

1. In a truck, a chassis, a tiltable body thereon having a keeper, a latch pivotally mounted upon the chassis for swinging movement over and into engagement with the keeper, and having a rounded eccentric lower face engageable with the keeper, a shaft upon which the latch is mounted, having a handle whereby the latch may be withdrawn from its engagement with the keeper, and a spring surrounding the shaft and acting thereon to urge the shaft in a direction to carry the latch into wedging engagement with the keeper.

2. In a vehicle, a chassis, a tiltable body mounted thereon and having a keeper, a latch pivotally mounted at its upper end upon the chassis above the keeper for swing-

ing movement over and into engagement with the keeper, said latch having a lower face adapted to have wedging engagement with the keeper, and manually operable means for withdrawing the latch from its engagement with the keeper.

3. In a vehicle, a chassis, a tiltable body mounted thereon and having a keeper, a latch pivotally mounted upon the chassis for swinging movement over and into engagement with the keeper, the latch having an eccentric lower face adapted to have wedging engagement with the keeper when the body is lowered, means acting to automatically lock the body in a tilted position and against reverse movement, and a single operable means for releasing the latch to permit the movement of the body to a tilted position and then movable to release the locking means to permit the body to return to its horizontal position.

4. In a vehicle, a chassis, a tiltable body mounted thereon for movement from a horizontal to a tilted position, said body having a keeper at its forward end, a prop formed in two sections, pivoted to each other and respectively pivoted to the chassis and to the body, a pivotally mounted latch carried by the chassis and adapted to engage said keeper as the body reaches a horizontal position, said latch having wedging engagement therewith, and manually actuatable means operatively connected to said latch to shift the latch from its engaging position and permit the tilting of the body, a lock carried by one of said sections of the prop and adapted to engage the other section of the prop when the sections are in aligned position to thereby hold the body in a tilted position, said latch actuating means shiftable to withdraw the prop lock and when the prop sections are in aligned position acting to operatively engage one section of the prop and cause the sections to move from the aligned position to thereby permit the body to move downward, and a spring urging the latch to a latching position.

5. In a truck, a chassis, a tiltable body having a keeper at its forward end, and means for holding the body lowered upon the chassis including a segmental member pivotally mounted upon the chassis for swinging movement in a vertical plane, the rear edge face of the segmental member being downwardly and forwardly inclined when the member is in its normal position, and the lower edge face of said member being eccentric to its pivotal center and adapted to have wedging engagement with the keeper when the body is lowered, a spring urging said latch toward the front of the body, and manually operable means for withdrawing the latch.

6. In a truck, a chassis, a body tiltably

mounted thereon for movement from a horizontal to a tilted position and vice versa, said body having a keeper at its forward end, a prop formed in two sections pivoted to each other and respectively pivoted to the chassis and to the body, one of said sections having a notch adjacent its pivotal connection with the other section, and the other section having a latch pivoted thereon and adapted to engage in said notch when the sections are in aligned position, a latch pivotally mounted upon the chassis and adapted to swing over and into engagement with the keeper, when the chassis is lowered, a manually operable shaft mounted upon the chassis and having an upwardly extending projection operatively connected to said second named latch, and a downwardly extending projection operatively connected to the first named latch whereby to simultaneously cause the retraction of both of said latches by said manually actuatable member.

7. In a vehicle, a chassis, a tiltable body thereon, means for holding the body tilted including a prop formed in two sections pivoted to each other, the sections being respectively pivoted to the body and to the chassis, a latch pivoted to the lowermost section and adapted to engage the uppermost section when the sections are in approximate alignment and the body is tilted to thereby hold the prop from breaking, a latch pivotally mounted upon the chassis for swinging movement in a vertical plane, said latch having a downwardly and forwardly inclined forward edge face eccentric to the pivotal center of the latch, a keeper mounted upon the body at its forward end and adapted to engage the forward edge of the latch to swing it rearward as the body descends and to be engaged by the eccentric lower face of the latch when the keeper has passed the latch, a manually actuatable shaft mounted upon the chassis and operatively engaging both of said latches, and a spring urging the shaft in a direction to shift the second named latch into the path of movement of the keeper.

8. In a truck, a chassis, a tiltable body thereon and means for holding the body lowered upon the chassis including a keeper on the body and a member pivoted at its upper end on the chassis above the keeper and swinging toward and over the keeper when the body is lowered and having wedging engagement with the keeper, and means urging the pivoted member into said wedging engagement.

9. In a truck, a chassis, a tiltable body thereon and having a keeper, and means for holding the body lowered upon the chassis including a latch pivoted at its upper end upon the chassis and above the keeper for swinging movement toward and over the keeper and having an eccentric lower face

engageable with and over the keeper, and means urging said latch toward the keeper.

10. In a truck, a chassis, a tiltable body thereon, the body having a transversely extending keeper, and means for holding the body lowered upon the chassis including a latch pivotally mounted upon the chassis

and adapted to swing over the keeper, the latch having an eccentric lower face engaging with the keeper, and a spring urging 10 said latch toward the keeper and into wedging engagement therewith.

In testimony whereof I affix my signature.

PERRY A. BRICK.
